CLAIM

The ornamental design for a storage container, as shown and described.

DESCRIPTION

FIG. 1 is a perspective view of the storage container having a lid;

FIG. 2 is a top plan view thereof;

FIG. 3 is a front elevational view thereof, the rear elevational view being a mirror image thereof;

FIG. 4 is a left side elevational view thereof, the right side elevational view being a mirror image thereof; and,

FIG. 5 is a bottom plan view thereof.
